UNITED STATES PATENT OFFICE

BIRD C. CLUTTER AND GEORGE E. WAGNER, OF AKRON, OHIO, ASSIGNEES, BY MESNE ASSIGNMENTS, TO CLUTTER-WAGNER, INC., A CORPORATION OF OHIO

FULL-REVOLVING EXCAVATOR

Application filed March 25, 1927. Serial No. 178,239.

This invention relates to excavators of the full-revolving type.

The general purpose of the invention is to provide interengaging means on the revolving deck and the table or support upon which it revolves, which normally are out of engagement but, upon a heavy load being applied to the deck, will engage with non-rolling friction to prevent teetering of the deck on the turntable during excavating operations thereby holding the line of the cut accurately and which, particularly in skimming roadways, hold the scoop to the grade and furthermore relieve the center pin on which the shovel pivots of severe strains.

Particularly the invention contemplates the provision of a flange on the table which supports the revolving deck and gibs on the under side of the deck embracing but normally not contacting with the flange so that any tendency for tilting of the deck is resisted by the supporting table and the tractor or other vehicle carrying the same, the gibs frictionally engaging the flange only upon a heavy load being applied to the deck as when crowding the scoop of the excavator.

The foregoing and other objects are obtained by the construction illustrated in the accompanying drawings and described below.

It is to be understood that the invention is not limited to the specific form thereof shown and described.

Of the accompanying drawings,

Figure 1 is a side elevation of an excavator embodying the invention, two types of excavating attachments being indicated thereon in dotted lines; and

Figure 2 is a section on line 2-2 of Figure 1.

Referring to the drawings, the numeral 10 designates a tractor and 11 an annular or circular table mounted thereon on which is supported a revolving deck 12 pivoting on a center pin 13.

The table 11 has a lateral flange 11^a thereon and at circumferentially spaced points on the under side of deck 12 are gibs 14, 14

embracing the flange 11^a, but normally out of engagement therewith.

At 15 there is indicated in dotted lines a skimmer attachment which, in crowding into the earth, produces a toggle action on the deck 12 tending to lift the front end upwardly. The gibs 14 engaging flange 11^a will, accordingly, be engaged with the flange and will tend to lift the whole forward end of the tractor 10 off the ground. This great weight on a leverage the length of the whole tractor offers such resistance to the lifting action of the skimmer 15 as to prevent its assuming a different angle than that at which it is initially crowded and thus a definite grade can be maintained.

At 16 there is indicated in dotted lines an excavator attachment of the ditcher type, the dipper stick being shown at 17. The thrust in this stick is upwardly and also tends to lift the forward end of deck 12, gibs 14 effectively preventing such action and thus assisting in maintaining a definite depth of cut.

The gibs 14, being normally out of engagement with flange 11^a, offer no frictional resistance whatever to the normal rotation or swinging of the deck as for dumping the scoop, but are only brought into play during a crowding action of the scoop.

It will be understood that the gibs 14 have similar beneficial results when other types of excavator attachments than are shown herein are used on deck 12. It will also be apparent that modifications of the invention may be resorted to without departing from the spirit thereof or the scope of the appended claim.

What is claimed is:

An excavator of the full-revolving type, comprising a vehicle, a circular table on the vehicle, a revolving deck bearing on the table, a pivot for the revolving deck on the vehicle at the center of the table, a lateral flange on the edge of the table, circumferentially spaced non-rotatable gibs on the under side of the deck extending under the flange and normally out of engagement therewith but adapted to engage under the flange with non-rolling friction when a heavy load

is applied to the deck to prevent teetering and sideplay thereof, and an excavator attachment on the forward end of the deck, including a boom tending to lift the forward end of the deck during an excavating operation.

BIRD C. CLUTTER.
